(57) **ABSTRACT**

A fluid cooled speaker having a T-yoke with a pole piece, a magnet surrounding the pole piece, a voice coil positioned between the pole piece and the magnet, and a cone connected to the voice coil. The T-yoke includes a body having a base and a pole piece with a sealed cavity formed within the pole piece. The T-yoke also has a fluid inlet and outlet formed in the body and communicating between the cavity and an area outside the body of the T-yoke.

FIG. 6C

help cool the voice coil. As noted above, if the temperature in the speaker components becomes too high, the voice coil is adversely affected. One solution attempted by the prior art is to provide an air passage 19 through a vented T-yoke 15 as seen in FIG. 1B. It is intended that the movement of cone 4 will induce a pumping action which will draw air into passage 19 and then expel it back out passage 19. Alternatively, dust cap 7 could be made from permeable material which would allow additional air exchange through dust cap 7. While this design may provide some cooling effect of T-yoke 15, the heat transfer rate between T-yoke 15 and air is significantly less than the heat transfer rate between a T-yoke and a circulating liquid.

FIGS. 3A-3D provide one preferred embodiment of the present invention, liquid cooled T-yoke 25. T-yoke 25 will generally comprise a pole piece 26 and a base 27. FIG. 3B illustrates how an interior cavity 33 will be formed in pole piece 26. A threaded base aperture 28 communicating with cavity 33 which will be formed in base 27. FIG. 3B also illustrates a base plug 30 having threaded surface 31 and barbed hose fittings 32 extending from fluid inlet 34 and fluid outlet 35. Base plug 30 also has an extension tube 36 extending above the height of threaded surface 31. While extension tube 36 is shown connected to inlet 34, it will be understood that extension tube 36 could just as readily be attached to outlet 35. FIG. 1C best illustrates how base plug 30 will further include a polygonal gripping surface 38 adapted for application of a wrench or similar tool. FIG. 1D illustrates how base plug 30 will be inserted into threaded base aperture 28 of T-yoke 25 and form a fluid tight seal between base aperture 28 and plug 30. When base plug 30 is inserted into T-yoke 25, extension tube 36 will be positioned in the upper portion 37 of cavity 33. In this manner, extension tube 36 helps insure that fluid will circulate through all portions of cavity 33 and effect the greatest heat transfer.

An alternate embodiment of the T-yoke is seen in FIGS. 4A-4C. T-yoke 40 differs from the previous embodiment in that the water circulating cavity is formed by way of two intersecting passages 42 being drilled through base 47 into the interior of pole piece 46. Threaded fluid hose fittings 41 may then be inserted into passages 42 in order to form a fluid inlet and outlet through fittings 41. Again hose fittings 41 have barbs which aid in retaining the hose on fittings 41.

A still further embodiment is seen in FIGS. 5A-5C. Here, the fluid cavity is formed (as best seen in FIG. 5C) by drilling two vertical passages 55 through base 57 and into pole piece 56. A horizontal connecting passage 52 is drilled through the upper portion of pole piece 56 such that vertical passages 55 will be connected. As suggested by FIG. 5A, the threaded apertures 53 remaining after the formation of passage 52 will be closed by way of threaded plugs 54 being inserted therein. Passage 52 could be made with or without the use of threads and a seal may be formed at the apertures 53 whether threaded or unthreaded by applying a heat resistant sealing compound such as liquid steel or epoxy. Alternatively, plugs 54 could be pressed or sintered into apertures 53 to form the necessary seals. FIG. 5B suggests how threaded fluid line fittings 51 will be inserted into the inlet and outlet apertures created at the bottom of vertical passages 55.

A still further embodiment is shown in FIGS. 6A-6C. In FIG. 6A, pole piece 66 is formed with a removable pole cap 68. As in FIGS. 5A-5C, vertical passages 65 will be drilled through base 67 and into pole piece 66. A cross channel 62 (see FIG. 6A) is then milled out of the top of the material separating the vertical passages 65. A gasket or O-ring 63

may be positioned around cross channel 62 and then pole cap 68 will be secured to pole piece 66 by way of screws 69. As before, threaded fluid line fittings 61 will be inserted into the inlet and outlet apertures created at the bottom of vertical passages 65.

FIGS. 7A-7D illustrate still another embodiment of the present invention. The embodiment in the FIG. 7 differs somewhat from previous embodiments in that the prior art air vented T-yoke 15 is converted to water cooled operation. 10 As suggested in FIG. 7B, the vent aperture 19 will have threads 80 formed therein. These threads 80 will be engaged by a, threaded sleeve cup insert 82. Cup insert 82 has a threaded outer surface 86 and a cavity 84 formed within cup insert 82. A threaded base opening 88 is also formed at the 15 bottom of cup insert 82. A fluid line fitting plug 81 will have a threaded collar 87 which is sized to engage the threads on base opening 88, with O-ring 83 forming a water tight seal between these elements. While not shown in the drawings, cup insert 82 could alternatively be formed without a 20 threaded outer surface 86, but sized to create a tight friction fit within vent aperture 19. Cup insert 82 could then be 25 pressed into place within vent aperture 19. Fitting plug 81 could also be formed without threaded collar 87. The base opening 88 on cup insert 82 could then be formed with an extended lip which would be rolled over the bottom of fitting plug 81 once fitting plug 81 was pressed into base opening 88.

Fitting plug 81 will include two hose fittings 89 which 30 form fluid inlet 34 and, outlet 35 and fitting plug 81 will further include a divider wall 85 (best seen in FIG. 7D) positioned above and between inlet 34 and outlet 35. FIG. 35 7D first illustrates fitting plug 81 with divider wall 85 seen from the side and further illustrates fitting plug 81 rotated 901 to show divider wall 85 from the front perspective. FIG. 7C demonstrates how sleeve cup insert 82 will be threaded into aperture 19 and fitting plug 81 threaded into base opening 88. In this configuration, the T-yoke 15 becomes 40 mechanically equivalent to the previously disclosed embodiments of the T-yoke which had cavities formed directly in the pole piece. As shown by FIG. 7C, cooling fluid will enter cavity 84 through inlet 34, circulate around divider wall 85 and exit outlet 35. As seen in FIG. 7D, divider wall 85 has a width "w" which will be approximately the width of cavity 84. It is not necessary that divider wall 85 form a seal with 45 the sides of cavity 84. It is only necessary that divider wall 85 is wide enough to direct a substantial portion of the cooling fluid entering cavity 85 over the top of divider wall 85 as opposed to around its sides. It will be understood that 50 divider wall 85 performs the same function as extension tube 36 (seen in FIG. 3B) in that it forces fluid circulation in the upper portion of the cavity 85. Preferably, cup insert 87 will be constructed of a highly conductive material, such as metal (aluminum, iron, etc.), so that cup insert 87 will readily 55 conduct heat from T-yoke 15 and allow transfer of the heat to fluid circulating through cavity 84.

FIG. 8 illustrates one embodiment of the fluid cooling system which will circulate cooling fluid to the fluid cooled speaker of the present invention. Speaker 1 is illustrated with the T-yoke 25 of the present invention. Heat from voice coil 10 will be transferred to T-yoke 25 and then to the fluid in cavity 33. The fluid in cavity 33 is circulated from outlet 35 to heat exchanger 76 by pump 75. As the fluid flows through heat exchanger 76, heat will be dissipated to the surrounding environment by vanes 77 on heat exchanger 76. The cooled 60 fluid will then be circulated back to cavity 33 by way of inlet 34. It will be understood that FIG. 8 is illustrative of only 65 one basic fluid cooling system. The system could also

5

include a separate fluid reservoir integrated therein. Additionally, various types of conventional heat exchange mechanisms could be employed, including eliminating the heat exchanger 76 and allowing the heat transfer to occur in a fluid reservoir. There are also a large variety of fluids which could be used to cool the present invention. These fluids include water, glycol, a water/glycol mixture and numerous oils.

Although certain preferred embodiments have been described above, it will be appreciated by those skilled in the art to which the present invention pertains that modifications, changes, and improvements may be made without departing from the spirit of the invention defined by the claims. All such modifications, changes, and improvements are intended to come within the scope of the present invention.

I claim:

1. A fluid cooled T-yoke for a loudspeaker, said T-yoke comprising:

- a. a body having a base and a pole piece with a sealed cavity formed within said pole piece, wherein said base has an aperture formed therein which communicates with said cavity and a base plug sealingly engages said aperture;
- b. a fluid inlet formed in said body and fluidly communicating between said cavity and an area outside said body and wherein said fluid inlet and fluid outlet are formed through said base plug; and
- c. a fluid outlet formed in said body and fluidly communicating between said cavity and an area outside said body.

2. The fluid cooled T-yoke according to claim 1, wherein said cavity has an upper portion and one of said fluid inlet or outlet includes an extension tube extending into said upper portion of said cavity to insure fluid circulates through said upper portion.

3. A fluid cooled loudspeaker having a T-yoke with a pole piece, a magnet surrounding said pole piece, a voice coil positioned between said pole piece and said magnet, and a cone connected to said voice coil, said T-yoke comprising:

5

6

a. a body having a base and a pole piece with a sealed cavity formed within said pole piece, wherein said base has an aperture formed therein which communicates with said cavity and a base plug sealingly engages said aperture;

b. a fluid inlet formed in said body and fluidly communicating between said cavity and an area outside said body; and

c. a fluid outlet formed in said body and fluidly communicating between said cavity and an area outside said body, wherein said fluid inlet and fluid outlet are formed through said base plug.

4. The fluid cooled loudspeaker according to claim 3, wherein said cavity has an upper portion and one of said fluid inlet or fluid outlet includes an extension tube extending into said upper portion of said cavity to insure fluid circulates through said upper portion.

5. A fluid cooled loudspeaker having a T-yoke with a pole piece, a magnet surrounding said pole piece, a voice coil positioned between said pole piece and said magnet, and a cone connected to said voice coil, said T-yoke comprising:

a. a body having a base and a pole piece with a sealed cavity formed within said pole piece;

b. a fluid inlet formed in said body and fluidly communicating between said cavity and an area outside said body;

c. a fluid outlet formed in said body and fluidly communicating between said cavity and an area outside said body; and

d. wherein said pole piece and said base include a threaded aperture such that a threaded sleeve cup insert engages said aperture in order to form said sealed cavity within said body.

6. The fluid cooled loudspeaker according to claim 5, wherein a fluid line fitting plug engages a bottom section of said sleeve cup insert and said fluid line fitting plug has a dividing wall extending upwards therefrom.
